UNITED STATES PATENT OFFICE.

GEORGE K. BAINBRIDGE, OF SAN FRANCISCO, CALIFORNIA.

CUTTING AND ROLLING MACHINE FOR PLASTIC MATERIALS.

1,192,156.

Specification of Letters Patent. Patented July 25, 1916.

Application filed August 25, 1915. Serial No. 47,304.

To all whom it may concern:

Be it known that I, GEORGE K. BAINBRIDGE, a citizen of the United States, residing at San Francisco, in the county of San Francisco, State of California, have invented a new and useful Cutting and Rolling Machine for Plastic Materials, of which the following is a specification in such full and clear terms as will enable those skilled in the art to construct and use the same.

This invention relates to a machine for cutting and rolling plastic materials such as cream candies which must be surfaced before some additional treatment is given to them.

It will be understood by those skilled in the art that while the machine is primarily intended for handling cream candies that it might equally well be used for a large number of other purposes.

An embodiment of the invention is shown in the drawing in which the same reference numeral is applied to the same portion throughout, but I am aware that there may be many modifications thereof.

Figure 1 is a side elevation of the complete machine, Fig. 2 is a plan view of the complete machine, Fig. 3 is a sectional view of the cutter and that portion of the machine which rolls the cut-off lumps of material, Fig. 4 is a vertical sectional view on the line 4—4, Fig. 2, Fig. 5 is a sectional view illustrating the supporting shaft upon which the upper belt frame slides, Fig. 6 is a sectional view illustrating the mounting of one of the rollers in the frames carrying the same, and Fig. 7 is a vertical sectional view illustrating another of the rollers carrying the rolling belt.

The numeral 1 represents a suitable base upon which the machine is mounted. This base has a pair of inverted U shaped frames 2 and 3, which frames support longitudinally extending bars 4 and 5, which bars form the support for two roller shafts 6 and 7. The bars 4 and 5 are braced by means of two bars 8 and 9 which are bolted to the frames 2 and 3 respectively. Connecting the bars 4 and 5 are cross pieces 10, 11, and 12 which form a support for the floor 13 upon which the endless belt 14 travels.

The endless belt 14 passes around rollers 15, 16 and over a small roll 17, which latter prevents the belt from sagging.

The shaft 6 is carried in boxes 20, 21 which are adjusted by means of the threaded

bolts 22, 23, suitable nuts 24, 25 being used to draw the roll up and hold the belt tight. The shaft 7 has a pulley 26 thereon for driving it, said pulley receiving power from a belt 27 which passes around a multiple pulley 28 on a short shaft 29 supported by the brace 8.

At the upper part of the frame there is secured a flat top member 30 for the support of the operating parts of the upper belt. This member 30 is adjustably supported by means of bolts 31, 32, 33 and 34 which bolts have nuts thereon in contact with the upper member of the U frames supporting the belt. On the sides the frames 2 and 3 support a horizontal bar 36 which bar supports a bracket 37 through which a shaft 38 extends, said shaft supporting two rollers 39, 40 over which a belt 41 extends from the multiple pulley 28 to a pulley 42 on the upper end of the crank shaft 43. The crank shaft is journaled in a box 44 suitably secured to the top member 30 and its lower end is connected to a shallow U shaped frame 45 in such manner as to permit it to rotate in said frame 45 and thus give a gyroscopic motion to the upper belt.

The upper belt is supported from the member 30 by means of four depending arms 46, 47, 48 and 49. Said arms carry two horizontal shafts 50, 51, on which shafts two longitudinally extending bars 52, 53 are slidable, said bars having outturned lugs at the ends as indicated at 54, 55 through which said shafts 50, 51 respectively pass. The bars 52, 53 are rigidly connected by two cross shafts 60, 61. The frame which supports the upper belt comprises two longitudinally extending bars 62, 63 rigidly connected together by means of the bolts 64, 65. This frame carries rollers 66, 67 at its ends, the latter being adjustable, and the bars 62, 63 are slidable on the bars 60, 61, which latter bars are connected with the supports 52, 53 slidable on the longitudinally extending rods 50, 51, so that the components of a lateral and longitudinal slide of the belt frame imparted by the shaft 43 and frame 45 will be a circular or gyroscopic movement.

The roll 67 is supported upon a shaft 68 which shaft is journaled in suitable bearings 69, 70, which bearings are rigidly connected to the threaded bolts 71, 72 and which bolts are acted upon by the nuts 73, 74 for shifting the roll 67 and tightening the belt 76 car-

- ried thereby. The roll 66 has a worm wheel 77 on its shaft at one end, which worm wheel is operated by the worm 78 on a flexible shaft 79, the latter shaft having as a bearing a bracket 80 and having its other end connected by means of a coupling 81 to the top of the crank shaft 43.
- 5 The flat member 30 carries a receptacle 83 for the comminuted material used for surfacing the lumps of material to be treated by the machine. This receptacle has a shaft 84 extending thereinto which shaft is supported by the bearing block 85 and driven from the pulley 86 by means of the belt 87
- 10 15 extending from the multiple pulley 28. The receptacle 83 is provided with a screen 88, the fineness of which determines the quantity of material that will be dropped on the belt 76 for the surfacing of the objects to be treated. It is to be observed that each of the roller shafts is provided with two bushings 89, 90 which are forced into the side members supporting said rollers in order to form bearings for said shafts.
- 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965
- The flat member 30 carries a receptacle 83 for the comminuted material used for surfacing the lumps of material to be treated by the machine. This receptacle has a shaft 84 extending thereinto which shaft is supported by the bearing block 85 and driven from the pulley 86 by means of the belt 87
- 15 extending from the multiple pulley 28. The receptacle 83 is provided with a screen 88, the fineness of which determines the quantity of material that will be dropped on the belt 76 for the surfacing of the objects to be treated. It is to be observed that each of the roller shafts is provided with two bushings 89, 90 which are forced into the side members supporting said rollers in order to form bearings for said shafts.
- 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965
- The machine is driven from a motor M on the base 1 which motor has a belt 114 in mesh with the pulley 115, a smaller pulley 116 on the shaft carrying the pulley 115 having a belt 117 passing over a larger pulley 118 on the shaft 119 carrying the gear 113. The shaft 119 also has a sprocket gear 120 thereon, over which a chain 121 passes to a sprocket gear 122 on the shaft 100, said

longitudinal travel, means to feed lumps of material intermittently on the lower belt, and means to dust flour on the upper belt from which it is discharged to the lower belt.

- 5 3. A confectionery rolling machine comprising a frame, having a fixed bed, an endless apron movable over the bed, a secondary frame supported in the first frame over its bed, means to vertically adjust said frame with respect to said bed, a second belt carried by said adjustable frame, means to move the adjacent faces of the belts in the same direction at different rates of speed,

a crank supported by the adjustable frame 15 and connected with the upper belt to give it a circular movement, and means to feed lumps of material to the lower belt so they will pass under the upper belt to be rolled thereby.

In testimony whereof I have hereunto set my hand this 19th day of August, A. D. 1915, in the presence of the two subscribed witnesses.

GEORGE K. BAINBRIDGE.
